(57) **CLAIM**

The ornamental design for a wearable chain, as shown and described.

DESCRIPTION

FIG. 1 is a top plan view of a wearable chain and including an enlarged partial top view showing six links;

FIG. 2 is an enlarged detail view of a portion of the wearable chain shown in FIG. 1;

FIG. 3 is a perspective view thereof;

FIG. 4 is a top plan view thereof;

FIG. 5 is a bottom plan view thereof;

FIG. 6 is a front elevational view thereof;

FIG. 7 is a rear elevational view thereof;

FIG. 8 is a right side elevational view thereof;

FIG. 9 is a left side elevational view thereof;

FIG. 10 is a top plan view of a wearable chain and including an enlarged partial top view of a second embodiment showing eight links;

FIG. 11 is an enlarged detail view of a second embodiment of a portion of the wearable chain shown in FIG. 10;

FIG. 12 is a perspective view of a second embodiment thereof;

FIG. 13 is a top plan view of a second embodiment thereof;

FIG. 14 is a bottom plan view of a second embodiment thereof;

FIG. 15 is a front elevational view of a second embodiment thereof;

FIG. 16 is a rear elevational view of a second embodiment thereof;

FIG. 17 is a right side elevational view of a second embodiment thereof;

FIG. 18 is a left side elevational view of a second embodiment thereof;

FIG. 19 is a top plan view of a wearable chain and including an enlarged partial top view of a third embodiment showing ten links;

FIG. 20 is an enlarged detail view of a third embodiment of a portion of the wearable chain shown in FIG. 19;

FIG. 21 is a perspective view of a third embodiment thereof;

FIG. 22 is a top plan view of a third embodiment thereof;

FIG. 23 is a bottom plan view of a third embodiment thereof;

FIG. 24 is a front elevational view of a third embodiment thereof;

FIG. 25 is a rear elevational view of a third embodiment thereof;

FIG. 26 is a right side elevational view of a third embodiment thereof;

FIG. 27 is a left side elevational view of a third embodiment thereof;

FIG. 28 is a top plan view of a wearable chain and including an enlarged partial top view of a fourth embodiment showing twelve links;

(Continued)

FIG. 29 is an enlarged detail view of a fourth embodiment of a portion of the wearable chain shown in FIG. 28; FIG. 30 is a perspective view of a fourth embodiment thereof; FIG. 31 is a top plan view of a fourth embodiment thereof; FIG. 32 is a bottom plan view of a fourth embodiment thereof; FIG. 33 is a front elevational view of a fourth embodiment thereof; FIG. 34 is a rear elevational view of a fourth embodiment thereof; FIG. 35 is a right side elevational view of a fourth embodiment thereof; FIG. 36 is a left side elevational view of a fourth embodiment thereof; FIG. 37 is a top plan view of a wearable chain and including an enlarged partial top view of a fifth embodiment showing fourteen links; FIG. 38 is an enlarged detail view of a fifth embodiment of a portion of the wearable chain shown in FIG. 37; FIG. 39 is a perspective view of a fifth embodiment thereof; FIG. 40 is a top plan view of a fifth embodiment thereof; FIG. 41 is a bottom plan view of a fifth embodiment thereof; FIG. 42 is a front elevational view of a fifth embodiment thereof; FIG. 43 is a rear elevational view of a fifth embodiment thereof; FIG. 44 is a right side elevational view of a fifth embodiment thereof; and, FIG. 45 is a left side elevational view of a fifth embodiment thereof.

The broken lines shown in the drawing views represent portions of the wearable chain which form no part of the claimed design.
